UNITED STATES PATENT OFFICE

110,390

DESIGN FOR A HINGED HASP

Sydney D. Friedman, Bronx, N. Y.

Application May 5, 1938, Serial No. 77,019

Term of patent 7 years

To all whom it may concern:

Be it known that I, Sydney D. Friedman, a citizen of United States of America, residing at Bronx, New York, have invented a new, original, and ornamental Design for a Hinged Hasp, of which the following is a specification, reference being had to the accompanying drawing, forming part thereof.

Fig. 1 is a front elevation of a hinged hasp showing my design, and

Fig. 2 is an end view of Fig. 1.

I claim:—

The ornamental design for a hinged hasp as shown.

SYDNEY D. FRIEDMAN.
